(57) **CLAIM**

The ornamental design for a potty trainer, as shown and described.

DESCRIPTION

FIG. 1 is a top, front and right-side perspective view showing our new design of a potty trainer;

FIG. 2 is a front elevational view thereof;

FIG. 3 is a rear elevational view thereof;

FIG. 4 is a top plan view thereof;

FIG. 5 is a bottom plan view thereof;

FIG. 6 is a left-side elevational view thereof;

FIG. 7 is a right-side elevational view thereof;

FIG. 8 is a top, front and right-side perspective view thereof isolated from other elements which are presented in broken lines in FIGS. 1 through 7;

FIG. 9 is a top plan view thereof isolated from other elements which are presented in broken lines in FIGS. 1 through 7; and,

FIG. 10 is a top, front and right-side exploded perspective view thereof with elements shown in broken lines.

The broken lines in the drawings depict portions of the potty trainer that form no part of the claimed design.

1 Claim, 10 Drawing Sheets
